(57) **ABSTRACT**

An inductor device includes a first trace, a second trace, and a second switch. The first trace includes a first sub-trace, a first switch and a second sub-trace. The first sub-trace includes a first line and a second line. The first switch is configured to switch the first sub-trace to the first line or switch the first sub-trace to the second line. The second sub-trace is coupled to one terminal of the first sub-trace at a first node. The second trace includes a third sub-trace and a fourth sub-trace. The fourth sub-trace is coupled to one terminal of the third sub-trace at a second node. The second switch is coupled to the first node and the second node.

INDUCTOR DEVICE

RELATED APPLICATIONS

This application is a Continuation-in-part of U.S. application Ser. No. 17/014,063, filed on Sep. 8, 2020, which claims priority to the benefit of U.S. Provisional Patent Application No. 62/898,618, filed on Sep. 11, 2019, and Taiwan Application Serial Number 109126927, filed on Aug. 7, 2020, the entire contents of which are incorporated herein by reference as if fully set forth below in its entirety and for all applicable purposes.

BACKGROUND

Field of Invention

The present disclosure relates to an electronic device. More particularly, the present disclosure relates to an inductor device.

Description of Related Art

Radio frequency (RF) devices generates second harmonic, third harmonic, etc. during operation. The harmonics cause negative effect to other circuits. For example, second harmonic of 2.4 GHz circuit is near 5 GHz, and 5 GHz signal causes negative effect to system on chip (SoC).

Conventional way to solve negative effect caused by harmonics is that a filter will be disposed outside of a circuit for filtering the harmonics or improving characteristic of the circuit and the inductor. However, the filter disposed outside of the circuit will affect function of the circuit and generate additional costs.

SUMMARY

The foregoing presents a simplified summary of the disclosure in order to provide a basic understanding to the reader. This summary is not an extensive overview of the disclosure and it does not identify key/critical elements of the present disclosure or delineate the scope of the present disclosure. Its sole purpose is to present some concepts disclosed herein in a simplified form as a prelude to the more detailed description that is presented later.

One aspect of the present disclosure is to provide an inductor device. The inductor device includes a first trace, a second trace, and a second switch. The first trace includes a first sub-trace, a first switch and a second sub-trace. The first sub-trace includes a first line and a second line. The first switch is configured to switch the first sub-trace to the first line or switch the first sub-trace to the second line. The second sub-trace is coupled to one terminal of the first sub-trace at a first node. The second trace includes a third sub-trace and a fourth sub-trace. The fourth sub-trace is coupled to one terminal of the third sub-trace at a second node. The second switch is coupled to the first node and the second node.

Therefore, based on the technical content of the present disclosure, the capacitor of the inductor device brings a function to filter low frequency, such that low frequency signal induced at the inductor device cannot pass but high frequency signal can pass the capacitor directly. Low frequency signal is, for example, a signal that uses 2.4 GHz as main operating frequency. An induced signal caused by the main operating frequency can be cancelled by the folded inductor of the inductor device. Therefore, the folded induct-

tor will not affect the characteristic of the operating frequency of the inductor. If an inductor which is located at the center of the inductor device has a high frequency signal, for example, a second harmonic (i.e., 5 GHz signal), the high frequency signal may pass the capacitor and form an inductive inductor which is a circle flows through the folded inductor and the capacitor. Therefore, a 5 GHz harmonic signal corresponding to 2.4 GHz signal is induced in the inductor device of the present disclosure. The 5 GHz signal can be used in the circuit. For example, the 5 GHz signal can be amplified and then the amplified 5 GHz signal is used to cancel the 5 GHz harmonic signal of the operating frequency. The amplifying circuit can be arranged by a designer who is familiar with circuit design. As a result, a negative effect to a 5 GHz circuit can be reduced. In addition, since the switch is used as filer, there is a filer disposed inside the inductor device. Therefore, there is no need to dispose a filter outside of the inductor device, so as to prevent an outer filter from affecting the circuit or prevent additional costs.

It is to be understood that both the foregoing general description and the following detailed description are by examples, and are intended to provide further explanation of the invention as claimed.

BRIEF DESCRIPTION OF THE DRAWINGS

The accompanying drawings are included to provide a further understanding of the invention, and are incorporated in and constitute a part of this specification. The drawings illustrate embodiments of the invention and, together with the description, serve to explain the principles of the invention. In the drawings,

FIG. 1 depicts a schematic diagram of an inductor device according to one embodiment of the present disclosure;

FIG. 2 depicts a schematic diagram of a partial structure of an inductor device shown in FIG. 1 according to one embodiment of the present disclosure;

FIG. 3 depicts a schematic diagram of an inductor device according to one embodiment of the present disclosure;

FIG. 4 depicts a schematic diagram of a partial structure of an inductor device shown in FIG. 3 according to one embodiment of the present disclosure;

According to the usual mode of operation, various features and elements in the figures have not been drawn to scale, which are drawn to the best way to present specific features and elements related to the disclosure. In addition, among the different figures, the same or similar element symbols refer to similar elements/components.

DESCRIPTION OF THE EMBODIMENTS

To make the contents of the present disclosure more thorough and complete, the following illustrative description is given with regard to the implementation aspects and embodiments of the present disclosure, which is not intended to limit the scope of the present disclosure. The features of the embodiments and the steps of the method and their sequences that constitute and implement the embodiments are described. However, other embodiments may be used to achieve the same or equivalent functions and step sequences.

Unless otherwise defined herein, scientific and technical terminologies employed in the present disclosure shall have the meanings that are commonly understood and used by one of ordinary skill in the art. Unless otherwise required by context, it will be understood that singular terms shall

include plural forms of the same and plural terms shall include the singular. Specifically, as used herein and in the claims, the singular forms “a” and “an” include the plural reference unless the context clearly indicates otherwise.

FIG. 1 depicts a schematic diagram of an inductor device **1000** according to one embodiment of the present disclosure. As shown in the figure, the inductor device **1000** includes a first trace **1100**, a second trace **1200**, and a switch **SW1**. In addition, the first trace **1100** includes a first sub-trace **1110** and a second sub-trace **1120**. A terminal of the first sub-trace **1110** and a terminal of the second sub-trace **1120** are coupled at a first node **N1**. The second trace **1200** includes a third sub-trace **1210** and a fourth sub-trace **1220**. A terminal of the third sub-trace **1210** and a terminal of the fourth sub-trace **1220** are coupled at a second node **N2**. The switch **SW1** is coupled between the first node **N1** and the second node **N2**. As shown in the figure, the inductor device **1000** further includes a connection element **1300** coupled between the other terminal of the first sub-trace **1110** and the other terminal of the third sub-trace **1210**. With respect to operations, when a low frequency signal is generated, the switch **SW1** is turned off, such that the low frequency signal cannot pass through the switch **SW1**. On the other hand, when a high frequency signal is generated, the switch **SW1** is turned on, such that the high frequency signal passes through switch **SW1** of the inductor device **1000** to form an induced inductor which is a circle flows through the inductor device **1000**. It is noted that, the present disclosure is not limited to the structures as shown in FIG. 1, and it is merely an example for illustrating one of the implements of the present disclosure.

FIG. 2 depicts a schematic diagram of a partial structure **1900** of the inductor device **1000** shown in FIG. 1 according to one embodiment of the present disclosure. As shown in the figure, the first sub-trace **1110** includes a first line **1111**, a second line **1113**, and a switch **SW2**. The switch **SW2** is configured to switch the first sub-trace **1110** to the first line **1111**, or switch the first sub-trace **1110** to the second line **1113**. In one embodiment, the length of the first line **1111** is larger than the length of the second line **1113**. Therefore, when the first sub-trace **1110** is switched to the first line **1111**, the inductance of the first sub-trace **1110** is larger. In contrast, when the first sub-trace **1110** is switched to the second line **1113**, the inductance of the first sub-trace **1110** is smaller.

In one embodiment, the first line **1111** includes a plurality of first wires **1111**, and the second line **1113** includes a second wire **1113**. Specifically, the first line **1111** is wound to form a plurality of first wires **1111**. Besides, the second line **1113** is the second wire **1113** as shown in the figure.

As shown in the figure, the switch **SW2** is configured to switch the first sub-trace **1110** to a plurality of first wires **1111**, or the switch **SW2** is configured to switch the first sub-trace **1110** to the second wire **1113**. Therefore, when the switch **SW2** is turned off, the signal is transmitted through a plurality of first wires **1111** of the first sub-trace **1110**. In contrast, when the switch **SW2** is turned on, the signal is transmitted through the second wire **1113** of the first sub-trace **1110**. In another embodiment, the plurality of first wires **1111** are located on a first layer, and the second wire **1113** is located on a second layer. In one embodiment, the first layer and the second layer are different layers.

In one embodiment, the second sub-trace **1120** includes a third line **1121**, a fourth line **1123**, and a switch **SW3**. The switch **SW3** is configured to switch the second sub-trace **1120** to the third line **1121**, or switch the second sub-trace **1120** to the fourth line **1123**. In one embodiment, the length

of the third line **1121** is larger than the length of the fourth line **1123**. Therefore, when the second sub-trace **1120** is switched to the third line **1121**, the inductance of the second sub-trace **1120** is larger. In contrast, when the second sub-trace **1120** is switched to the fourth line **1123**, the inductance of the second sub-trace **1120** is smaller.

In one embodiment, the third line **1121** includes a plurality of third wires **1121**, and the fourth line **1123** includes the fourth wire **1123**. Specifically, the third line **1121** is wound to form a plurality of third wires **1121**. Besides, the fourth line **1123** is the fourth wire **1123** as shown in the figure.

As shown in the figure, the switch **SW3** is configured to switch the second sub-trace **1120** to a plurality of third wires **1121**, or the switch **SW3** is configured to switch the second sub-trace **1120** to the fourth wire **1123**. Therefore, when the switch **SW3** is turned off, the signal is transmitted through the plurality of third wires **1121** of the second sub-trace **1120**. In contrast, when the switch **SW3** is turned on, the signal is transmitted through the fourth wire **1123** of the second sub-trace **1120**. In another embodiment, the plurality of third wires **1121** are located on the first layer, and the fourth wire **1123** is located on the second layer. In one embodiment, the first layer and the second layer are different layers.

In one embodiment, the fourth wire **1123** and the plurality of first wires **1111** are overlapped to each other partially. In another embodiment, the fourth wire **1123** and the plurality of third wires **1121** are overlapped to each other partially. In still another embodiment, the second wire **1113** is not overlapped to the plurality of first wires **1111** and the plurality of third wires **1121**. In one embodiment, the plurality of first wires **1111** and the plurality of third wires **1121** are disposed to each other in an interlaced manner. For example, the disposition sequence of the plurality of first wires **1111** and the plurality of third wires **1121** can be “the first wire **1111**, the third wire **1121**, the first wire **1111**, the third wire **1121**, and the first wire **1111**.”

Reference is now made to FIG. 1, in one embodiment, the first sub-trace **1110** and the second sub-trace **1120** all include a first terminal and a second terminal. As shown in the figure, the first terminal (e.g. the upper terminal) of the first sub-trace **1110** and the first terminal (e.g. the upper terminal) of the second sub-trace **1120** are coupled at the first node **N1**. Besides, the third sub-trace **1210** and the fourth sub-trace **1220** all include a first terminal and a second terminal. As shown in the figure, the first terminal (e.g. the upper terminal) of the third sub-trace **1210** and the first terminal (e.g. the upper terminal) of the fourth sub-trace **1220** are coupled at the second node **N2**.

In one embodiment, the first sub-trace **1110** and the second sub-trace **1120** are disposed at the first side (e.g. the left side of the figure) of the inductor device **1000**, and the third sub-trace **1210** and the fourth sub-trace **1220** are disposed at the second side (e.g. the right side of the figure) of the inductor device **1000**. In another embodiment, the first side and the second side are located at opposite sides of the inductor device **1000**.

Reference is now made to FIG. 2, in one embodiment, the inductor device **1000** further includes a first connection member **1400**. The first connection member **1400** includes a first terminal and a second terminal. As shown in the figure, the first terminal (e.g. the upper terminal in the figure) of the first connection member **1400** is coupled to the first line **1111** and the second line **1113** respectively at a node **N4** and a node **N5**. The second terminal (e.g. the lower terminal in the figure) of the first connection member **1400** is coupled to the first line **1111** of the first sub-trace **1110**. In another embodiment

ment, the first connection member 1400 is located on the second layer, and the first sub-trace 1110 is located on the first layer.

In one embodiment, the inductor device 1000 further includes a second connection member 1500. The second connection member 1500 includes a first terminal and a second terminal. As shown in the figure, the first terminal (e.g. the upper terminal in the figure) of the second connection member 1500 is coupled to the third line 1121 and the fourth line 1123 at the same point (e.g. the N3 in the figure). The second terminal (e.g. the lower terminal in the figure) of the second connection member 1500 is coupled to the third line 1121 of the second sub-trace 1120. In another embodiment, the second connection member 1500 is located on the second layer, and the second sub-trace 1120 is located on the first layer. It is noted that, although only the partial structure 1900 disposed at the upper-left corner of the inductor device 1000 of the present disclosure is illustrated in FIG. 2, the same partial structure 1900 can be used at the lower-left corner, the upper-right corner, and the lower-right corner of the inductor device 1000, such that different lines can be generated by the switch of the partial structure 1900. Besides, the present disclosure is not limited to the structures as shown in FIG. 2, and it is merely an example for illustrating one of the implements of the present disclosure.

FIG. 3 depicts a schematic diagram of an inductor device 1000A according to one embodiment of the present disclosure. Compared with the inductor device 1000 shown in FIG. 1, the inductor device 1000A shown in FIG. 3 further includes a capacitor C. The capacitor C is coupled between the first node N1 and the second node N2. In one embodiment, the capacitor C and the switch SW1 are disposed to each other in parallel. It is noted that, the element in FIG. 3 (e.g., a first trace 1100A, a second trace 1200A, a first sub-trace 1110A, a second sub-trace 1120A, a third sub-trace 1210A, a fourth sub-trace 1220A, a connection element 1300A), whose symbol is similar to the symbol of the element in FIG. 1, has similar structure feature in connection with the element in FIG. 1. Therefore, a detail description regarding the structure feature of the element in FIG. 3 is omitted herein for the sake of brevity. Besides, the present disclosure is not limited to the structure as shown in FIG. 3, and it is merely an example for illustrating one of the implements of the present disclosure.

FIG. 4 depicts a schematic diagram of a partial structure of the inductor 1000A device shown in FIG. 3 according to one embodiment of the present disclosure. As shown in the figure, the capacitor C and the switch SW1 are disposed to each other in parallel at the first terminal point N1 and the second terminal point N2. With respect to operations, when the switch SW1 is turned off, the capacitor C is regarded as a filter for filtering low frequency signal, and let the high frequency signal pass through. It is noted that, the present disclosure is not limited to the structures as shown in FIG. 4, and it is merely an example for illustrating one of the implements of the present disclosure.

It can be understood from the embodiments of the present disclosure that application of the present disclosure has the following advantages. The inductor device of the present disclosure may induce high frequency signal (e.g., second harmonic) of inductor inside the inductor device. After the high frequency signal is amplified by additional circuit, the amplified high frequency signal is able to cancel negative effect to the circuit caused by second harmonic. For example, the capacitor of the inductor device is used to let high frequency signal pass and block low frequency signal. Therefore, the inductor device is able to deal with signals in

high frequency or low frequency by two kinds of inducing manner. In addition, since the filter (e.g. the capacitor C) is disposed inside integrated circuit (IC), for example, the inductor device, of the present disclosure, there is no need to dispose a filter outside of the inductor device, so as to prevent an outer filter from affecting the circuit or prevent additional costs.

Although the present invention has been described in considerable detail with reference to certain embodiments thereof, other embodiments are possible. Therefore, the spirit and scope of the appended claims should not be limited to the description of the embodiments contained herein.

It will be apparent to those skilled in the art that various modifications and variations can be made to the structure of the present invention without departing from the scope or spirit of the invention. In view of the foregoing, it is intended that the present invention cover modifications and variations of this invention provided they fall within the scope of the following claims and their equivalents.

What is claimed is:

1. An inductor device, comprising:
a first trace, comprising:

a first sub-trace;
a first switch, configured to connect the first sub-trace to one of a first line and a second line, wherein lengths of the first line and the second line are different, wherein the first sub-trace is connected to the first line when the first switch is turned off, wherein the first sub-trace is connected to the second line when the first switch is turned on; and

a second sub-trace, coupled with a terminal of the first sub-trace at a first node;

a second trace, comprising:

a third sub-trace; and
a fourth sub-trace, coupled with a terminal of the third sub-trace at a second node; and
a second switch, coupled between the first node and the second node.

2. The inductor device of claim 1, wherein the first line comprises a plurality of first wires, and the second line comprises a second wire, wherein the first switch is configured to connect the first sub-trace to the first wires or the second wire, wherein the first sub-trace is connected to the first wires when the first switch is turned off, wherein the first sub-trace is connected to the second wire when the first switch is turned on.

3. The inductor device of claim 2, wherein the first wires are located on a first layer, and the second wire is located on a second layer.

4. The inductor device of claim 3, wherein the second sub-trace, wherein the second trace comprises:

a third switch, configured to connect the second sub-trace to one of the third line and the fourth line, wherein lengths of the third line and the fourth line are different, wherein the second sub-trace is connected to the third line when the third switch is turned off, wherein the second sub-trace is connected to the fourth line when the third switch is turned on.

5. The inductor device of claim 4, wherein the third line comprises a plurality of third wires, and the fourth line comprises a fourth wire, wherein the third switch is configured to connect the second sub-trace to the third wires or the fourth wire, wherein the second sub-trace is connected to the third wires when the third switch is turned off, wherein the second sub-trace is connected to the fourth wire when the third switch is turned on.

6. The inductor device of claim 5, wherein the third wires are located on the first layer, and the fourth wire is located on the second layer.

7. The inductor device of claim 6, wherein the fourth wire and the third wires are overlapped to each other partially.

8. The inductor device of claim 7, wherein the fourth wire and the first wires are overlapped to each other partially.

9. The inductor device of claim 8, wherein the second wire is not overlapped to the first wires and the third wires.

10. The inductor device of claim 9, wherein the first wires and the third wires are disposed to each other in an interlaced manner.

11. The inductor device of claim 1, wherein the first sub-trace comprises:

a first terminal; and

a second terminal;

wherein the second sub-trace comprises:

a first terminal; and

a second terminal, coupled with the second terminal of the first sub-trace at the first node.

12. The inductor device of claim 11, wherein the third sub-trace comprises:

a first terminal; and

a second terminal;

wherein the fourth sub-trace comprises:

a first terminal; and

a second terminal, coupled with the second terminal of the third sub-trace at the second node.

13. The inductor device of claim 12, wherein the first sub-trace and the second sub-trace are disposed at a first side

of the inductor device, and the third sub-trace and the fourth sub-trace are disposed at a second side of the inductor device.

14. The inductor device of claim 13, wherein the first side and the second side are located at opposite sides of the inductor device.

15. The inductor device of claim 14, further comprising:

a first connection member, comprising:

a first terminal, coupled to the first line and the second

line; and

a second terminal, coupled to the first sub-trace.

16. The inductor device of claim 15, wherein the first connection member is located on a second layer.

17. The inductor device of claim 16, wherein the second sub-trace comprises a third line and a fourth line, wherein the inductor device further comprises:

a second connection member, comprising:

a first terminal, coupled with the third line and the fourth line at a same point; and

a second terminal, coupled to the second sub-trace.

18. The inductor device of claim 17, wherein the second connection member is located on the second layer.

19. The inductor device of claim 18, further comprising:

a capacitor, coupled between the first node and the second

node.

20. The inductor device of claim 19, wherein the capacitor and the second switch are coupled to each other in parallel.
